LLOYD W. MOULTON AND OSCAR C. KAVLE, OF SYRACUSE, NEW YORK.

CENTRIFUGAL BABBITTING MACHINE.

Application filed May 3, 1927. Serial No. 188,478.

This invention relates to a centrifugal babbittting machine for casting Babbitt metal bearings or linings in journal boxes and other hollow objects by pouring the molten metal into the hollow object and simultaneously rotating the latter at a sufficiently high rate of speed to cause the molten metal to impinge against the inner walls of the object and to gradually build up by centrifugal force as the pouring continues until the desired thickness of the babbitt is attained leaving a central cylindrical bore of pre-determined diameter according to the amount of molten metal introduced into the hollow object.

The main object is to provide a more compact, expeditious and efficient method of and apparatus for casting babbitt or equivalent metal linings or bearings in hollow objects than has heretofore been practised.

One of the specific objects is to provide means for supporting and rotating the work about a horizontal axis with the axis of the portion of the object to be lined substantially coincident with its axis of rotation so as to produce a uniform distribution of the molten metal lining circumferentially around and within the work.

Another object is to enable the work to be clamped and released upon and from the rotary supporting member and also to enable the rotary member to be started and stopped at will from one and the same side of the machine and within easy reaching distance of the operator when pouring the molten metal into the work.

Other objects and uses relating to specific parts of the machine will be brought out in the following description.

40 In the drawings:

Figure 1 is a vertical sectional view of a centrifugal babbittting machine embodying various features of the invention.

Figure 2 is a horizontal sectional view taken in the plane of line 2—2, Figure 1.

Figure 3 is a transverse vertical sectional view taken in the plane of line 3—3, Figure 1, except that portions of the fan or blower case and adjacent parts are broken away.

50 This machine is adapted to be used more particularly for casting Babbitt metal linings in the journals of connecting rods or pitmen commonly used in piston engines or pumps for transmitting motion from a ro-

tary crank shaft to the piston but obviously 55 may be used for casting similar metal linings in other hollow objects.

As illustrated, the machine comprises a hollow upright column or base —1— upon which is pivotally mounted at —2— a horizontal shelf —3— carrying a hollow case section —4— and a circular shield section —5—, the case section —4— and shield section —5— being bolted or otherwise secured to the upper face of the shelf section —3— 65 to form a substantially unitary part thereof.

The pivotal connections —2— between the base section —1— and shelf section —3— are preferably located at one side of both of those parts to permit the shelf section with 70 the various other parts carried thereby to be tilted laterally to and from a position across the upper end of the base section —1—, the opening tilting movement of the shelf section being limited by a cable connection 75 —6— between the parts —1— and —3— as shown in Figure 1.

The case section —4— is located mainly at the rear of the machine and is provided with a removable cap section —4'— which is 80 joined to the section —4— in approximately the horizontal plane of the axis of the rotary work-supporting shaft hereinafter described.

The shield section —5— is arranged in an upright position mainly at the front of the 85 machine and co-axial with the work-supporting shaft previously mentioned to protect the operator against contact with the revolving work.

A horizontal shaft —7— is journaled in 90 suitable bearings —8— in the upper portion of the frame section —4— to extend forwardly and rearwardly of the frame and carries at its forward end a circular wheel or disk —9— having its hub —10— projecting 95 rearwardly therefrom and keyed or otherwise secured to the adjacent end of the shaft —7— to rotate therewith directly in front of the front bearing —8—.

The front end of the hub —10— is re- 100 cesssed to receive a nut —11— which engages the adjacent threaded end of the shaft —7— to assist in holding the wheel —9— against forward displacement from the shaft.

The front end of the wheel —9— is also 105 provided with a central recess for receiving the rear end of a forwardly projecting work-clamping ring —12— which is bolted or oth-

erwise secured to the wheel —9— to rotate therewith and is provided with a central opening —13— gradually increasing in diameter from front to rear to form what may 5 be termed an air and gas chamber.

The hub of the wheel —9— is provided with a circular row of air and gas passages 14 leading from the rear end of the chamber —13— rearwardly and outwardly to the 10 rear face of the wheel at the outside of its hub as shown in Figure 1 to permit the escape of air and gas from the molten metal during the casting operation.

A fan or blower —15— is secured to the 15 rear face of the wheel —9— around the hub —10— and circular row of passages —14— with its suction side communicating with said passages for circulating the air and gases from the mold and discharging them 20 through openings —15'— in the periphery of the fan.

The case section —4— is provided with a hub —16— projecting forwardly therefrom toward the fan —15— and concentric with 25 the shaft —7— for receiving and supporting the front bearing —10— and also for additionally supporting the rear end of the hub of the wheel —9—.

A ring —17— is slidable lengthwise of 30 and upon the hub —16— just at the rear of the fan —15— and is provided with a plurality of, in this instance three, forwardly projecting bolts —18— arranged in uniformly spaced relation circumferentially 35 around and beyond the periphery of the clamping ring —12— so as to extend some distance forwardly beyond the front end of said ring for receiving and supporting an additional clamping plate —19—.

40 The intermediate portions of these bolts —18— are reciprocally movable forwardly and rearwardly in suitable guide bushings —20— which are firmly secured in openings in the wheel —9— to extend forwardly 45 therefrom as shown in Figure 1.

The rear ends of the bolts extend through the interior of the fan —15— and are firmly secured to the ring —17— which, as previously stated, is movable axially and effects a 50 corresponding axial movement of a front clamping plate —19— through the medium of the bolts —18—.

Suitable coiled springs —21— are interposed between the plate —7— and rear ends 55 of the bushings —20— around the adjacent portions of the bolts —18— for automatically forcing the ring —17—, bolts —18— and clamping plate —19— rearwardly to cause the clamping plate —19— to yieldingly clamp the work against the front face 60 of the companion plate —12— as shown by dotted lines in Figure 1.

The front clamping plate —19— is provided with a rearwardly tapered circular 65 opening —22— co-axial with the axis of the

shaft —7— for receiving the molten babbitt or other metal which is to form the inner lining or journal bearing of the hollow portion of the work as, for example, a connecting rod or pitman —a— as shown by dotted 70 lines in Figure 1.

The portion of the pitman which is to receive the molten metal lining is usually divided diametrically but is provided with a more or less circular opening therethrough 75 which, when the work is placed in operative position, is aligned with the axis of the shaft —7— and, therefore, with the openings —13— and —22— in the clamping plates —12— and —19— respectively.

The outer ends of the pitmen are usually provided with openings for connection with the coupling pins on the piston and in order that the pitman may be held against angular movement relatively to the wheel —9— during the casting operation, said wheel is provided with a forwardly projecting stud —23— adapted to enter the opening in the outer end of the pitman —a— as shown in 90 Figure 1.

The clamping member —19— is provided with rearwardly projecting sleeves —24— surrounding the adjacent portions of the bolts —18— and telescoping with the front ends of the bushings —20— to assist in guiding said head in its forward and rearward movements.

The wheel —9— and its clamping members —12— and —19— carried thereby constitutes what may be termed the work-holder 100 while the members —12— and —19— may be termed the work-clamping for holding and releasing the work

Clamp opening means.

A cross shaft —25— is journaled in suitable bearings —26— Figure 3, on the case section —4— and is provided with a pair of crank arms —27— extending upwardly therefrom at opposite sides of the hub —16— for engaging the rear face of the plate —17—.

An additional shaft —28— is journaled in a sleeve —29— on the case section —4— in a plane below and parallel with the shaft —25— and is provided with a crank arm —30— connected by a link —31— to an additional crank arm —32— on the shaft —25— as shown more clearly in Figure 3.

This shaft —28— extends beyond the outer end of its bearing sleeve —29— and is provided with a hand lever —33— by which it may be rocked at will for moving the clamping member —19— forwardly against the action of its retracting springs —21— as, for example, when placing the work in operative position between the clamping members for casting the Babbitt metal lining therein and for removing the work when the casting operation is com- 130

pleted, it being understood that the springs —21— are sufficiently strong to hold the work firmly between the clamping members.

5   *Driving and controlling means.*

A stationary brake drum —34— is secured to the inner face of the front portion of the case —4— co-axial with and around the shaft —7— and is provided with an inner 10 conical friction face —34— projecting rearwardly for engagement with a suitable clutch member presently described.

A pulley —35— is loosely journaled upon bearings —36— on the shaft —7— at the 15 rear of and in axially spaced relation to the brake drum —34— and has its front end provided with a conical friction face —35'— adapted to be engaged by the clutch member previously mentioned.

20   A clutch member —38— is splined on the shaft —7— between the brake drum —34— and pulley —35— for axial movement thereon and also to rotate therewith and has its opposite ends provided with 25 conical friction faces —39— and —40— adapted to engage the inner friction faces —34'— and —35'— of the brake drum —34— and pulley —35— respectively as the clutch member —38— is shifted axially 30 in reverse directions for stopping and starting the rotation of the shaft —7— and work-holder carried thereby.

The spline connection between the clutch member —38— and shaft —7— preferably 35 consists of a key —41— seated in suitable key-ways in the shaft —7— and hub of the clutch-member —38— as shown in Figure 2.

Clutch shifting means.

40   The rear end of the shaft —7— is hollow to form a central lengthwise guide opening —42— for receiving front and rear plunger sections —43— and —44— which are arranged co-axially end to end for relative 45 endwise movement and are yieldingly connected by an interposed coiled spring —45— for a purpose presently described, the rear end of the front section —43— being reduced in diameter and extended into a corresponding socket in the adjacent front end of the rear section —44— as shown more clearly in Figure 2.

The front plunger section —43— is operatively connected to the hub of the clutch member —38— by means of a pin —45— which passes through an elongated slot —46— in the adjacent portion of the shaft —7— to allow sufficient endwise movement of the clutch member to engage and disengage the conical faces of the brake drum —34— and pulley —35—.

55   The adjacent ends of the plunger sections —43— and —44— are splined to each other by means of a pin —47— on the rear reduced end of the section —43— engaging

in a lengthwise slot —48— in the adjacent portion of the section —44— thereby causing both plunger sections to rotate in unison and at the same time permitting limited endwise movement of the plunger section —43—.

The rear end of the shaft —7— is threaded and engaged by a nut —50— which in turn engages the adjacent rear end face of the case —4— to hold the shaft against 75 forward movement, said shaft being also provided at its rear end with a socket of relatively larger diameter than the plunger section —44— for receiving a coiled spring —51— surrounding the adjacent portion of 80 said plunger section —44—.

The plunger section —44— is provided with a reduced threaded extension beyond the rear end of the shaft —7— engaged by suitable nuts —52— against which the rear 85 end of the spring —51— is adapted to rest, said extension being also provided at its rear end with an end-thrust bearing —53— as shown in Figure 1.

A bell-crank lever —54— is pivoted at 90 —55— to the rear side of the case —4— to extend vertically therefrom and has its upper end engaged with the rear face of the end-thrust bearing —53— and its lower end connected by a link —56— to a crank arm 95 —57— which is rigidly clamped to the inner end of the sleeve —29— to extend rearwardly therefrom as shown in Figures 1 and 3.

The outer end of the sleeve —29— is provided with an end lever —58— by which the sleeve and its crank arm —57— may be rocked or adjusted angularly for moving the plunger sections —44— and —43— endwise against the action of the spring —51— 105 and thereby effecting a corresponding movement of the clutch member —38— into engagement with the brake drum —34— immediately following its disengagement from the pulley —35—.

The hub of the lever —57— is provided with a downwardly extending projection —59— movable across and to opposite sides of the upper end of a vertically movable detent —60— which is yieldingly held in its uppermost position by a spring —61— situated in a socket in a forwardly projecting bracket —62— on the case section —4— as shown in Figure 1 whereby the lever —57— and parts actuated thereby may be 110 yieldingly held in its two extreme positions of adjustment while at the same time permitting adjustment to either of the extreme positions as may be required for stopping and starting the rotation of the shaft —7— 115 and work-holder carried thereby.

The lever —57— is provided with a stop —63— adapted to engage an overlying portion —64— of the case section —4— for 120 limiting the movement of the lever and 125

parts operated thereby to one position against the action of the retracting spring —51—.

The hub of said lever —57— is provided with a stop —65— adapted to engage an underlying screw —66— on the bracket —62— to limit the movement of the lever in the opposite direction under the action of the spring —51—, the screw —66— being adjustable to assure the engagement of the clutch member —38— with the pulley —35—.

A motor —67— is mounted upon the underside of the shelf or table —3— for movement therewith into and out of the upper end of the column —1—, said motor having its armature shaft provided with a pulley —68— which is connected by a belt —69— to the pulley —35— on the shaft —7—.

20 A belt tightener —70— is supported by a pivoted arm —71— on the motor case for effecting a motor positive driving of the supporting shaft for the work-holder.

25 Operation.

In casting the bearing or lining in the hollow work as —a— the lever —33— is first operated to open the clamping member —19— forwardly away from its companion 30 clamping member —12— after which the hollow part of the work to which the lining is to be cast is placed between the clamping members —12— and —19— with its axis substantially co-incident with the axis of 35 the shaft —7— and if the work is a pitman, the outer end of the pitman will be engaged with a stud —23— after which the pressure upon the lever —33— is released to allow the springs —21— to operate the 40 clamping member —19— for clamping the work between said member and its companion clamping member —12—.

During this preparation of the work for casting the lining therein the lever —58— will have been adjusted to hold the clutch member —38— into frictional engagement with the brake drum —34— and out of engagement with the pulley —35— to prevent the rotation of the work-holder.

50 When the work is properly clamped in the work-holder in the manner described the hand lever —58— will be adjusted to withdraw the clutch member —38— from engagement with the brake drum —34— and to engage it with the then rotating pulley —35— for transmitting rotary motion to the shaft —7— and to the work-holder and to the work carried thereby.

While the work-holder with the work 60 therein is being rotated a pre-determined quantity of molten metal as may be required to produce the desired thickness of the lining is poured through the inlet opening —22— in the clamping member —19— and 65 thence into the interior of the hollow por-

tion of the work in which the lining is to be cast.

The molten metal will, of course, be deposited by its own gravity upon the lower side of the opening in the work and as the work is rotated will be drawn out by centrifugal force against the walls of said opening until the limited quantity of molten metal is exhausted which determines the 75 thickness of the lining.

The speed of rotation of the work will, of course, be sufficient to cause the molten metal to firmly impinge against the walls of the opening in the work and to gradually build up inwardly and uniformly about the axis of rotation until the molten metal has cooled sufficiently to retain its form.

During this casting operation any air or gas which may be present in the mold or hollow work will be drawn out and expelled 85 to the exterior of the machine by the rotation of the fan 15.

This entire casting operation requires but a very short time and produces a lining of uniform thickness with a substantially cylindrical opening therethrough which may be quickly and accurately finished by boring if desired.

When the casting operation is complete 95 the lever —58— is readjusted to disengage the clutch member —38— from the pulley —35— and to reengage it with the brake drum —34— for stopping the rotation of the work after which the lever —33— may be adjusted to release the clamping head 100 —19— and allow the work to be withdrawn from its holder, the machine being then ready for a repetition of the operation just described.

105 What we claim is:—

1. In a metal casting machine, a work-holder having co-axial clamping members rotatable about a horizontal axis and provided with co-axial openings for permitting the entrance of molten metal into the work and for allowing air to escape from the work respectively, said members being relatively movable axially to grip and release the work, and a fan rotating with the work-holder and having its suction side connected to the air opening.

2. In a metal casting machine, a frame, a horizontal shaft journaled on the frame, a work-holder secured to the shaft and provided with a co-axial inlet for molten metal, a stationary brake drum and a rotary loose pulley arranged in axially spaced relation co-axial with the shaft, a clutch-member splined on the shaft, and means for moving the clutch-member axially into and out of engagement with the pulley and brake-drum.

3. In a metal casting machine, a frame, a horizontal shaft journaled on the frame, a work-holder secured to the shaft and pro-

- vided with a co-axial inlet for molten metal, a stationary brake drum and a rotary loose pulley arranged in axially spaced relation coaxial with the shaft, a clutch-member 5 splined on the shaft, and means for moving the clutch-member axially into and out of engagement with the pulley and brake-drum, said means having a portion thereof 10 slidable endwise in a central lengthwise opening in the shaft.
4. In a metal casting machine, a frame, a horizontal shaft journaled on the frame, a work-holder secured to the shaft and provided with a co-axial inlet for molten metal, a stationary brake drum and a rotary loose 15 pulley arranged in axially spaced relation co-axial with the shaft, a clutch-member splined on the shaft, and means for moving the clutch-member axially into and out of engagement with the pulley and brake-drum, said means including a hand-lever and resilient connections between the hand 20 lever and clutch-member.
5. In a metal casting machine, work-holder parts rotatable about a horizontal axis and relatively movable for holding and releasing the work, one of said parts having a co-axial opening for permitting the entrance of molten metal into the work, a stationary 25 brake-drum and a rotary loose pulley arranged in axially spaced relation co-axial with the work-holder, a rotary clutch-member movable axially into and out of engagement with the pulley and brake- 30 drum, means for transmitting rotary motion from the clutch-member to the work-holder, and means for shifting the clutch member axially.
- 35 6. In a metal casting machine, work-holder parts rotatable about a horizontal axis and relatively movable for holding and releasing the work, one of said parts having
- a co-axial opening for permitting the entrance of molten metal into the work, a stationary brake drum and a rotary loose 45 pulley arranged in axially spaced relation co-axial with the work-holder, a rotary clutch-member movable axially into and out of engagement with the pulley and brake 50 drum, means for transmitting rotary motion from the clutch-member to the work-holder, hand-levers movable about a common axis, means for transmitting motion from one of the levers to one of the axially movable parts of the work-holder, and means actuated by the other lever for shifting the clutch-member axially.
7. In a centrifugal babbittting machine, a frame, a horizontal shaft journaled on the frame, a wheel secured to the shaft and provided with a work-engaging stud some distance from its axis, work-clamping members mounted on the wheel coaxial therewith and provided respectively with a co-axial molten-metal inlet and a coaxial air- 65 and-gas outlet, one of said clamping members being spring-pressed toward the other, a rotary fan carried by the wheel and having its suction side connected to the air-and-gas outlet, means operable at will for shifting the movable clamping member axially away from its companion member, a non-rotatable brake-drum and a rotary loose pulley arranged in axially spaced relation co-axial with said shaft, means for rotating the pulley, a clutch member splined on the shaft and movable axially into and out of engagement with the pulley and brake-drum, and means operable at will for shifting the clutch member axially. 70
